DESIGN FOR A CHANDELIER

Herbert Friedenwald, Washington, D. C.

Application December 24, 1935, Serial No. 60,279

Term of patent 14 years

To all whom it may concern:

Be it known that I, Herbert Friedenwald, a citizen of the United States, residing in the city of Washington, District of Columbia, have invented a new, original, and ornamental Design for a Chandelier, of which the following is a specification, reference being had to the accompanying drawing, forming part thereof.

In the drawing:

I claim:

The ornamental design for a chandelier substantially as shown.

In testimony whereof, I affix my signature.

HERBERT FRIEDENWALD.
